PROCESS OF TREATING HYDROCARBON OIL

Percival C. Keith, Jr., Port Washington, N. Y.,
assignor to Gasoline Products Company, Inc.,
Newark, N. J., a corporation of Delaware

Application June 16, 1933, Serial No. 676,127

11 Claims. (CL 196—48)

This invention relates to processes and apparatus for the production of gasoline from raw crude oil.

In the treatment of raw crude oil to produce gasoline it has heretofore been generally customary to form from the crude oil either by distillation alone or distillation coupled with mild cracking, a distillate stock suitable for charging to a major cracking operation, this stock being subsequently treated under cracking conditions of heat and pressure to produce the desired gasoline product. In carrying on a process of this character it has usually been customary to separate various oil fractions and to regard them somewhat in the nature of by-products which are more suitably treated in independent operations, or even classified as marketable products without further processing. For example, a well known method is to separate from raw crude oil a gas oil charging stock which is thereafter subjected to cracking in a separate operation, complete in itself, to produce gasoline. This gasoline in many cases has been of such character as to require further processing, such as reformation and stabilization, to form a final gasoline product complying with the desired specifications. Likewise in many instances it has been found desirable, prior to the separation of the gas oil, to top the raw crude and subject the resulting unvaporized portion to a light cracking operation of a viscosity breaking nature whereby the content of gas oil may be increased. Various additional steps in the processing of crude oil for the production of gasoline have also been undertaken independently.

It is an object of my invention to provide a unitary process for the treatment of raw crude oil whereby all the operations necessary to produce a maximum amount of gasoline of final desired end point and characteristics may be carried out at the same time in a series of interlocking steps so related one to the other that a minimum amount of heat and attention are necessary, and high efficiency results. By combining all of the various steps which have heretofore been performed individually or in some incomplete combination one with the other, it is possible to utilize more advantageously heat which might otherwise be wasted, and also keep at a low figure the amount of labor and supervision necessary in the operation of a system to carry out the process.

More specifically it is an object of my invention to combine in a single unitary process for the treatment of raw crude oil, the steps of topping the raw crude, viscosity breaking the topped

crude, cracking a clean condensate stock, reforming any necessary portion of the gasoline produced to raise its anti-knock value to the desired point, and stabilizing gasoline distillate resulting from these operations to give a final desired product of the proper end point and vapor pressure. 5

The above mentioned and further objects and advantages of my invention, and the manner of attaining them will be made clear in the following description taken in conjunction with the accompanying drawings. 10

In the drawings Figures 1 and 1a represent together a schematic view in side elevation and partly in section of a combination cracking unit constructed in accordance with my invention and 15 Fig. 2 is a simplified flow diagram thereof.

Referring more particularly to the drawings, reference numeral 1 indicates a crude flash tower; 2 an evaporator; 3 a viscosity breaking furnace; 4 a vapor phase furnace; 5 a soaking drum; 6 a 20 fractionator; 7 a primary gas separator and 8 a stabilizer tower.

Charging oil, for example 37° A. P. I. Mid-Continent crude, is introduced through the charging line 9 and is forwarded by action of the pump 10 25 through heat exchangers 11, 12, 13, and 14, whereby it is raised to a temperature sufficient to cause the vaporization of light naphtha, for example 450° F. more or less. The amount of light naphtha so vaporized will vary according to the character of the crude and may represent about 10% to 30% of the initial charging stock and the gravity of this naphtha may be in the neighborhood of 67 to 71° A. P. I., e. g. 70° A. P. I. The raw crude thus preheated is then introduced into primary flash drum 15 of the crude flash tower 1 30 wherein vapors are released. This primary section is provided with fractionating devices such as bubble trays 16. Light virgin naphtha is withdrawn through vapor line 17 and after passing through one element of the heat exchanger 11 travels through final condenser 18 into storage drum 19. Light virgin naphtha may be withdrawn from the drum 19 and introduced through pipe 20 having valve 121, into the top of the primary flash drum 15 as a refluxing medium or 35 cooling oil, by action of pump 21. The unvaporized portions of the raw crude charging oil, which may be at a temperature of from 410°-440° F. for example, are passed from drum 15 into secondary flash drum 22 through pipe 23, having liquid level control valve 23', which serves to maintain a desired liquid level in drum 15. 40

In the secondary flash drum further vaporization of the introduced liquid takes place, this 45

being mainly caused by contact with hot vapors derived from the tar flasher 24, the vapors from the tar flasher passing upwardly through pipe 25 and heat exchanger 26 into the lower part of 5 the secondary flash drum, and maintaining a temperature therein of, for example 520 to 575° F., preferably about 535° F. These vapors enter the drum below baffle plates 27 while the unvaporized liquid from the primary flash drum enters 10 above these plates. The products vaporized by heat of the vapors from the tar flasher pass upwardly through bubble trays or similar devices 28 and 29, cooling oil or refluxing medium being supplied through pipe lines 30 and 31, valves 33 15 and 34 serving to regulate the amount of reflux so supplied. The refluxing medium supplied through pipe line 31 may be heavy naphtha withdrawn from accumulator drum 80 by action of pump 32, while the liquid introduced through 20 pipe line 30 is preferably a light gas oil from a receiver 38, which is forced by pump 58 through conduit 122 into pipe line 30. A trap out tray 35, which is positioned at an intermediate point in secondary flash drum 22 just above the point of entrance of the reflux pipe 30, serves to collect 25 clean light gas oil which is drawn off through line 37 and directed into receiver 38. The temperature of the liquid in the tray may be about 450° to 550° F., for example, 475° F. and the amount of gas oil so withdrawn may represent 30 about 12% of the initial charge, the gravity of the gas oil being, for example, about 36° A. P. I. Overhead vapors are withdrawn through pipe 80' and are introduced into the accumulator drum 35 80 after passing through condenser coil 180. The vapors so withdrawn consist primarily of heavy naphtha of, for example, about 46° A. P. I. gravity, and may represent, for example, 19% of the initial charge. The heavy unvaporized liquid 40 remaining in the bottom of the secondary flash drum and consisting of reduced crude including heavy gas oil and other unvaporized portions of the raw crude charging stock, and condensed portions of the vapors from the fuel oil flash 45 drum having a gravity of, for example, about 22° A. P. I., is withdrawn through drawoff line 39 and heat exchanger 26, and is forced by action of pump 41 through pipe 40 and heat exchanger 42 into an intermediate point in the evaporator 50 tower 2. The temperature of the reduced crude is increased by heat derived from the heat exchangers 26 and 42, prior to its introduction into the evaporator. For example, the temperature of the heavy oil may be about 535° F. in the base 55 of the second flash tower 650-670° F. after passing through heat exchanger 26 and 700-715° F. after passing through heat exchanger 42. The temperature increase resulting from passing the heavy oil through these exchangers might be 60 greater or less than that mentioned, depending on the amount and temperature of the hot products available for heat exchange. This heavy oil enters the evaporator above baffle plates or other fractionating devices 43 and flows downwardly 65 over these plates against the upwardly rising vapors of the evaporator, onto trap out tray 44. The liquid collected on trap out tray 44, which may be stripped of light fractions by water introduced through line 44', flows by gravity 70 through pipe 45 into accumulator drum 46, which has a vent line 123 for conducting any vapors back to the evaporator 2. The quantity of liquid so withdrawn may be, for example, about .39% reduced crude from the charge and 75 61% recycle stock, although these percentages

are subject to variation depending on the stock being treated, and the operating conditions. The entire amount of withdrawn liquid may be for example, approximately 145 to 150% although this percentage would be subject to wide variations, depending on the charging stock used, and operating conditions generally, for example, from less than 100% to more than 200% with respect to the initial charging stock. The gravity of this composite stock charged to the viscosity breaking furnace may be about 22° A. P. I. Oil may be passed from pipe 40 directly to this accumulator drum, through pipe 125 having valve 126 whenever desired, for control purposes. Liquid collected in the accumulator drum 46 is withdrawn through pipe 47 and forced by action of pump 48 through the heating coils of the viscosity breaking furnace 3. The temperature of the product entering the furnace may be approximately the same as that of the liquid when 10 drawn off from the trap out tray 44, e. g. 750-800° F. Upon entering the furnace the charge oil travels in two parallel streams, each controlled by a manually operable valve or an automatic flow regulator 47', first through shield 15 coils in the portion of the convection section of the furnace nearest the combustion chamber, indicated by reference numeral 49, next upwardly through radiant coils in the combustion chamber 50 of the furnace and finally through a 20 soaking coil in a cooler portion 51 of the convection section of the furnace, concurrent with the furnace gases, the final temperature attained by the oil being sufficient to promote a moderate amount of cracking, e. g. sufficient to 25 convert the oil into 8 or 10% gasoline and 22-24% charging stock for the vapor phase furnace. This temperature may be from 840-880° F., about 30 850° F. being generally preferable. Reference numeral 165 indicates the bridge wall of the 35 furnace.

The hot oil after leaving furnace 3 flows through the conduit 52 into the lower portion of evaporator 2, preferably without any substantial reduction of pressure. The evaporator is preferably operated at a moderate pressure, for example 195-215 pounds per square inch. The heating of the charge in the viscosity breaker furnace causes a moderate amount of cracking and therefore the products introduced into the 45 base of the evaporator tower contain lighter fractions which vaporize, the vapors passing upwardly through the evaporator tower. The upward passage of the vapors is obstructed by baffle plates 53 located below the trap out tray 44 and 50 bubble trays or other fractionating devices 54 located above the trap out tray, as well as by the baffle plates 43 already mentioned. A relatively light clean stock is introduced both above the baffle plates 53 through pipe 55, and above 55 the bubble trays 54 through pipe 56, as a refluxing medium, in order to promote fractionation of the rising vapors. The liquid introduced may advantageously be light gas oil, delivered through a common supply line 57 into which oil withdrawn from the gas oil receiver drum 38 is forced by pump 58. Valves 59 and 60 are furnished for controlling the amount of refluxing medium admitted. The vapors remaining uncondensed pass off from the top of the evaporator through vapor line 61 at a temperature of, for example, about 750-760° F. and are introduced into the fractionator or bubble tower 6 at an intermediate point. These vapors then rise upwardly through the tower, being subjected to the fractionating 65 70 75

action of baffle plates 62 and bubble trays 63. Pipe line 64 is provided for introducing a light clean refluxing medium, such as the light gas oil already mentioned, into the fractionator 6 at an intermediate point above the baffle plates 62. This pipe line may have an adjustable cooling device 65 whereby the temperature of the introduced oil may be varied, valve 66 being furnished to regulate the amount of refluxing medium supplied. 5

10 Refluxing liquid for the bubble trays in the top of the fractionator is provided by withdrawing liquid from a tray near the top of the tower, cooling this liquid by indirect heat exchange with the raw crude oil in heat exchanger 13 and returning the cooled liquid to the top of the tower. Pipe line 67, which circulates the refluxing medium, is provided with a pump 68, a control valve 168 and an auxiliary cooler 69 having control valve 168' that serves additionally to cool the 15 circulated liquid and to control the end point of the gasoline. An automatic thermostatic device 69' serves to maintain constant the end point of the gasoline derived from the tower 6, by increasing the amount of liquid passing through cooler 69, upon a rise in the temperature of the overhead vapors in the tower and vice versa. This fractionator is preferably operated under substantially the same pressure as that of the evaporator tower 2.

20 30 Gasoline vapors remaining uncondensed by the fractionating action of the tower are removed from the top thereof through vapor line 70 and passed through condenser 71 into the primary gas separator 7. The temperature of the vapors leaving the tower may be, for example, approximately 435° F. and that of the condensed liquid in the gas separator 80° F. The lower part of the fractionator tower 6 acts as a liquid reservoir while above the liquid level and below the vapor inlet to the tower are bubble trays 72 and an 35 accumulator pan 73. The accumulator pan collects part of the light gas oil reflux condensate formed during the fractionation of the vapors and this condensate is conducted in desired quantities either directly through drawoff line 74 and heat exchanger 14 into the light gas oil accumulator 38, or through pipe line 75 and heat exchanger 76 into the accumulator drum 38, or both. The condensate so drawn off may have a 40 gravity of about 25° A. P. I., sufficient being removed to maintain the level in drum 38. Any excess of condensate not withdrawn from the pan 73 overflows into the lower part of the fractionator. Valves 128 and 77 provide the necessary control for regulating the flow of the condensate. Water may be introduced into the fractionator or bubble tower 6 through pipe 170 to aid in stripping gasoline fractions from the reflux condensate. The temperature of the liquid in the lower part of the fractionator may be about 45 700° F. and that of the liquid in the accumulator 38, 500° F. thereabouts. Additional oil may be introduced into accumulator 38 from an external source through line 154, whenever necessary.

50 60 A reducing valve or orifice 78 serves to reduce the pressure on the condensate prior to its introduction into the drum 38, after passing through heat exchanger 14, and a similar reducing valve or orifice 79 performs a similar function for the condensate subsequent to its passage through heat exchanger 76.

65 75 Light virgin naphtha from the storage drum 19 is forced through pipe line 81 by action of pump 21, into the primary gas separator 7. This gas separator may be maintained under a pres-

sure slightly less than that of the fractionator tower, for example 175 pounds per square inch when the fractionator pressure is 200 pounds per square inch. The gasoline distillate mixture contained in the gas separator 7 is roughly freed from incondensable gases, which pass off through gas line 83 while the remaining distillate is withdrawn from the primary gas separator and forced by pump 84 through pipe line 85 and heat exchanger 86 into the stabilizer tower 8. The distillate enters at an intermediate point in the tower above a plurality of bubble trays 87 and below a larger number of bubble trays 88. Below the bubble trays 87 an accumulator pan 89 is positioned which serves to collect liquid products that are circulated through pipe line 90 and heat exchanger 76 by pump 91, the heated liquid being returned to the stabilizer below the accumulator pan 89. The heat exchanger 76 acts as a reboiler for the distillate in the base of the stabilizer column. Stabilized gasoline of the desired end point, automatically regulated by adjustment of valves 168 and 168', for example 400° F., is withdrawn from the bottom of the stabilizer through pipe line 92, heat exchanger 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

Reflux condensate collecting in the base of fractionator 6, being a clean stock having a gravity of about 25° A. P. I. and a color of about 3 N. P. A., for example, as well as a relatively low carbon content, of preferably not over .1% by the Conradson test, is withdrawn through pipe line 102 and forced by action of pump 103, through vapor phase furnace 4 and the connected soaking drum 5, wherein the condensate is subjected to cracking in the vapor phase, preferably at a temperature of less than 1000° F. and more than 850° F., most desirably 900-950° F., and a pressure of 100 to 400 pounds per square inch, most desirably 195 to 225 pounds per square

inch. The cracking to gasoline per pass is preferably in the neighborhood of 15 to 20%, the greatest part of this conversion being effected at temperatures above 850° F. These moderate cracking conditions have been found to produce a relatively high anti-knock gasoline without the simultaneous formation of excessively large amounts of fixed gas or heavy products such as tar or coke. The anti-knock rating of the gasoline produced can be increased, if desired, by increasing the temperature, or the percentage of cracking to gasoline per pass. The vapor phase charge may be, for example, in the range of 160 to 200% with respect to the quantity of initial charging stock for the system. A considerable proportion of the products from the vapor phase coil may be recovered by condensation and recycled, this amounting for example to about 70% of the total charge to the coil. The stock subjected to vapor phase cracking is preferably at least as clean as stated hereinbefore since less clean stocks tend to form objectionable carbon deposits in the cracking apparatus.

The cracked products leave the furnace and flow into soaking drum 5 through conduit 104, preferably without any substantial reduction in pressure. The soaking drum is preferably operated at substantially the same pressure as that of the evaporator tower and fractionation tower, e. g. 195 to 225 pounds per square inch. In the soaking drum additional cracking takes place, the soaked vapors passing overhead through pipe line 105 having pressure control valve 105' and flowing into the lower part of the evaporator tower adjacent the point of entrance of the cracked stock from the viscosity breaking furnace, and below the level of baffle plates 53. The temperature of the vapors leaving the soaking drum 5 is somewhat less than that of those entering the drum, for example about 835° F., when the inlet temperature is about 935° F. A light, clean, entirely vaporizable liquid, such as light gas oil, is introduced into the top of the soaking drum adjacent the vapor outlet in order to prevent coking of the vapor line. This may be done through pipe line 106 which connects with pipe 57 leading to the light gas oil storage drum 38. Pipe line 57 has heat exchanger 12 and line 106 has exchanger 93, as well as auxiliary cooler 107 therein whereby the temperature of any gas oil introduced into the soaking drum is reduced to a suitable value. Cross-over line 106' having valve 107' is furnished for introducing cool oil directly into the vapor line when additional cooling is desired. Coil 93, connected by pipe 93' with pipe line 106, serves to cool the oil in the soaking drum adjacent to the point of connection of the emergency circulating and draw-off line 129, thereby inhibiting coke deposition at this outlet. The line 129, which is used largely as a circulating line during the bring-up period is provided with valve 129'. The amount of oil passing through the cooling coil may be regulated by means of valves 130, 131', and 132'. The charging stock passes through vapor phase furnace 4 in two parallel streams which are symmetrically arranged. Each stream passes first through a convection coil located in the cooler portion 108 of the convection section of the furnace, countercurrent to the furnace gases, then upwardly through a radiant coil consisting of two tubes in parallel located in combustion chambers 109 of the furnace and finally downwardly concurrent with the furnace gases, through a soaking coil consisting of three tubes

in parallel and located in the hotter portion 110 of the convection section of the furnace. Reference numerals 166 and 167 indicate the furnace bridge walls. The convection coil raises the temperature of the oil relatively slowly, while the radiant coil increases the temperature more quickly to a higher value to promote cracking, and the soaking coil holds the temperature substantially constant at that value. Upon leaving the furnace the two streams unite for introduction into the soaking drum. The inlet pressure of the vapor phase coils may be, for example, about 420 pounds per square inch and the outlet pressure just sufficient to force the cracked products into the evaporator 2, e. g. 200 pounds per square inch. The pressure drop through the cracking coils would, of necessity, be dependent on the physical characteristics of the particular coils used.

The amount of cracking accomplished in the coils of the vapor phase furnace may be, for example, 13 to 15% per pass, while due to the additional cracking accomplished in the soaking drum 5, the total amount of vapor phase cracking per pass may be somewhat higher, for example 18 to 19%.

A light tar residue having a gravity of, for example, about 16° A. P. I., is withdrawn from the bottom of evaporator 2, through pipe line 111 having a reducing valve 149, and introduced into tar flasher drum 24 at an intermediate point in a series of baffle plates 112. The temperature of the oil in the flash drum is somewhat lower than in the bottom of the evaporator, e. g. 725 to 775° F. This drum is held under reduced pressure, preferably substantially atmospheric, and the vapors evolved therein pass upwardly through vapor line 25 and heat exchanger 26 into the lower part of secondary flash drum 22, in the manner already discussed hereinbefore. A light clean oil reflux such as light gas oil may be introduced above the baffle plates 112 through pipe line 113 connected to conduit 122. Fuel oil is withdrawn from the bottom of flash drum 24 through drawoff line 155 having a cooler 156 and a pump 157 therein. A portion of the cooled fuel oil may be by-passed through cross-over line 158 to line 113 for use as a refluxing medium, if desired, control being effected by valve 159. A cross-over line 160 having valve 161, is also furnished whereby light gas oil may be introduced into line 155 to reduce the viscosity of the fuel oil. Line 111' is provided so that hot vapors from the evaporator may be introduced into drum 24 whenever necessary to maintain the desired temperature. The point of connection of 111' to the evaporator is higher than that of 111 so that vapors may be withdrawn rather than liquid oil.

The heavy naphtha accumulated in drum 80 is stripped of its light products of a gasoline nature by aid of fractionator or stripper tower 131 to which vapors from the drum 80 pass by way of line 132. The fractionated vapors of a gasoline nature pass overhead through vapor line 133, are condensed in coil 134 and stored in reservoir 135, while reflux condensate is returned from the fractionator to the drum 80 by conduit 136. A draw-off line 137, pump 138 and pipe 139 having control valve 141 are furnished for returning gasoline from the reservoir 135 to fractionator 131 as a refluxing medium, and a conduit 140 having control valves 142 serves to conduct gasoline from pump 138 to pipe line 64 as a refluxing medium in bubble tower 6, whenever desired. Light naphtha

from drum 19 may be used in like manner by opening valve 82 in cross over line 82', particularly in starting up.

Heavy stripped naphtha, having a gravity of, for example, about 46° A. P. I., is removed from the accumulator drum 80 and forced by action of pump 32 through pipe line 114 leading to reforming coil 115 positioned in vapor phase furnace 4. The temperature of the naphtha entering the reforming coil may be 200-300° F. and its temperature upon leaving the coil after passage through the furnace may be from 950 to 1050° F., preferably about 1000° F., whereby a conversion to about 57% of high anti-knock gasoline, 18% gas oil, 5% fuel oil and 19% gas results. The converted material travels through pipe 116 which connects with the evaporator 2 at substantially the same level as pipe 52.

In normal operation it is preferable that the heavy naphtha to be reformed be that separated from the crude charge, that is, perhaps 15% to 20% of the crude charge, this being in amount about 10% to 15%, for example, with respect to the quantity of oil charged to the viscosity breaking operation, but in certain cases it may be desirable to increase this amount by including with it some or all of the gasoline stripped from the charge, or even to add naphtha from an external source through pipe 114' having pump 32'. The inclusion of some of the gasoline would increase the anti-knock value of the final product produced by the system but would also tend to increase gas losses and otherwise lower the operating efficiency. When a lower anti-knock final product is desired the amount of heavy naphtha reformed may be less than the total amount stripped from the charge. In any event the amount of reformed naphtha introduced into the evaporator is small with respect to the amount of stock supplied thereto by the viscosity breaking heater and vapor phase furnace. In its passage through the furnace the naphtha to be reformed first flows upwardly through a coil section 117 located in the convection portion of the furnace 4, then through a coil section 118 symmetrically arranged in the radiant portions of the furnace. A cooling liquid such as light gas oil is introduced into the transfer line 116 adjacent its point of connection with the furnace in order to prevent coke formation in the line. Pipe line 152, having control valve 153, interconnects gas oil line 51 with line 116 for this purpose. The outlet temperatures of the reformed naphtha may be maintained constant by valve 116' automatically regulated by thermostatic controller 117' coupled to the transfer line 116. The pressure on the naphtha entering the reforming coil may be about 800 pounds per square inch and its pressure on leaving the coil may be about 600 pounds per square inch, for example, the pressure then being reduced, by passage through valve 206, to that existing in the evaporator.

A pipe line 143 having a pump 144 and control valve 145 serves to circulate evaporator bottoms through heat exchanger 42, thereby heating the topped crude passing through line 40 and supplying cooling to the bottom of the evaporator sufficient to maintain the temperature thereof below a coking value, e. g. 810-830° F. The line 143 may connect with the pipe 105 at several points along the length thereof, indicated by numerals 400, 401, 402, and 403, so that the cooled oil is mixed with the hot vapors from the soaking drum 5, or it may be connected directly into the bottom of the evaporator. The drop of temperature of the hot

vapors from soaking drum 5 by introduction of cooled oil from line 143 into line 105, may be about 15° F. for example. By introducing cooling oil at a plurality of spaced points along vapor line 105 local deposition of coke, which tends to occur where a single point of introduction is used, is avoided. By putting the cooling or fluxing stock in at a plurality of points complete drying out of the cooling stock in the line is prevented. Connection 147 provides a path whereby cracked products from the bottom of soaking drum 5 may be passed directly from line 129 into the light tar line 111 leading to the flash drum 24, under control of valve 148. A similar connection 150 having control valve 151 is supplied so that desired amounts of cracked products may be introduced directly into the base of the fractionator. These lines are mainly used in starting up.

The vapor phase furnace has two separately and independently fired combustion chambers or radiant sections, and a common convection section. Each one of the symmetrical vapor phase coils located in portions 108 and 109 of the furnace, has two tubes in parallel, and each coil in the soaking section 110 three tubes in parallel, as already mentioned. In order to insure an equal amount of heating of the oil passed through each vapor phase path a separate flow controller 119 is provided for each path and in addition a temperature controller 120 preferably located at the end of the radiant coil section just prior to its connection with the soaking section, is provided for each path likewise. The flow controllers maintain constant the flow of oil through each of the parallel paths, while the temperature controllers regulate the amount of fuel supplied to each combustion chamber in such manner as to insure the proper constant outlet temperature for each path. The temperature of the reformed naphtha is independently regulated as described hereinbefore, if desired.

Valves 200, 201, and 202 are provided for controlling the flow through their associated lines; the valve 202 may be of the pressure reducing type if desired. Valves 47' serves as the primary control of the supply of oil to the viscosity breaking furnace. Valves 203 and 204 are provided to control the flow through their associated lines while the necessary control for the vapor phase cracking operation is effected primarily by valves 119. Valve 204 may be of the pressure reducing type if desired, while valves 205 and 206 serve to control the reforming operation, any desired pressure regulation being effected by valve 206.

I prefer to use the temperatures and pressures already mentioned, for the viscosity breaking, cracking and reforming operations, particularly for producing gasoline of approximately 70 octane number, from a charging stock such as 37° A. P. I. Mid-Continent crude, but somewhat higher or lower temperatures and pressures may be used, the exact conditions being determined in each case by the character of the charging stock and the specifications of the final desired products. Furthermore, whenever desired, the pressures of the several cracking operations may be adjusted independently to selected values to produce known effects on the individual stocks being treated. And the octane number and other characteristics of the final desired product may be regulated by varying the cracking temperature the cracking per pass of the individual stocks, or the total amount of cracking of these stocks. The parallel flow furnaces disclosed may be re-

placed by conventional single path furnaces, if desired.

While I have described a particular embodiment of my invention for the purposes of illustration it should be understood that various modifications and adaptations thereof may be made within the spirit of the invention as set forth in the appended claims.

I claim:

- 10 1. The process of treating hydrocarbon oil which comprises introducing relatively heavy oil comprising residual constituents and lighter constituents into a stripping zone wherein said oil is separated into vapors and a liquid residue, removing said residue from said stripping zone and passing residue so removed through a first cracking zone wherein it is raised to a cracking temperature and subjected to conversion while passing in a stream of restricted cross-sectional area 15 through a heating zone, introducing the resulting cracked products into an evaporating zone wherein vapors separate from liquid residue, fractionating vapors evolved from said oil in said stripping zone to form a condensate suitable for 20 use as clean cracking stock, passing condensate so derived through a second cracking zone wherein it is raised to a cracking temperature and subjected to conversion while passing in a stream of restricted cross-sectional area through a heating zone, introducing the resulting cracked products into said evaporating zone wherein vapors separate from liquid residue, fractionating vapors evolved from said oil in said stripping zone to form a condensate suitable for 25 use as clean cracking stock, passing condensate so derived through a second cracking zone wherein it is raised to a cracking temperature and subjected to conversion while passing in a stream of restricted cross-sectional area through a heating zone, introducing the resulting cracked products into said evaporating zone wherein vapors separate from liquid residue, fractionating vapors evolved from said oil in said stripping zone to form a condensate suitable for 30 use as clean cracking stock, passing condensate so derived through a second cracking zone wherein it is raised to a cracking temperature and subjected to conversion while passing in a stream of restricted cross-sectional area through a heating zone, introducing the resulting cracked products into said evaporating zone wherein vapors separate from liquid residue, fractionating vapors evolved from said oil in said stripping zone to form a condensate suitable for 35 use as clean cracking stock, passing condensate so derived through a second cracking zone wherein it is raised to a cracking temperature and subjected to conversion while passing in a stream of restricted cross-sectional area through a heating zone, introducing the resulting cracked products into said evaporating zone wherein vapors separate from liquid residue, fractionating vapors evolved from said oil in said stripping zone to form a condensate suitable for 40 use as clean cracking stock, passing condensate so derived through a second cracking zone wherein it is raised to a cracking temperature and subjected to conversion while passing in a stream of restricted cross-sectional area through a heating zone, introducing the resulting cracked products into said evaporating zone wherein vapors separate from liquid residue, fractionating vapors evolved from said oil in said stripping zone to form a condensate suitable for 45 use as clean cracking stock, passing condensate so derived through a second cracking zone wherein it is raised to a cracking temperature and subjected to conversion while passing in a stream of restricted cross-sectional area through a heating zone, introducing the resulting cracked products into said evaporating zone wherein vapors separate from liquid residue, fractionating vapors evolved from said oil in said stripping zone to form a condensate suitable for 50 use as clean cracking stock, passing condensate so derived through a second cracking zone wherein it is raised to a cracking temperature and subjected to conversion while passing in a stream of restricted cross-sectional area through a heating zone, introducing the resulting cracked products into said evaporating zone wherein vapors separate from liquid residue, fractionating vapors evolved from said oil in said stripping zone to form a condensate suitable for 55 use as clean cracking stock, passing condensate so derived through a second cracking zone wherein it is raised to a cracking temperature and subjected to conversion while passing in a stream of restricted cross-sectional area through a heating zone, introducing the resulting cracked products into said evaporating zone wherein vapors separate from liquid residue, fractionating vapors evolved from said oil in said stripping zone to form a condensate suitable for 60 use as clean cracking stock, passing condensate so derived through a second cracking zone wherein it is raised to a cracking temperature and subjected to conversion while passing in a stream of restricted cross-sectional area through a heating zone, introducing the resulting cracked products into said evaporating zone wherein vapors separate from liquid residue, fractionating vapors evolved from said oil in said stripping zone to form a condensate suitable for 65 use as clean cracking stock, passing condensate so derived through a second cracking zone wherein it is raised to a cracking temperature and subjected to conversion while passing in a stream of restricted cross-sectional area through a heating zone, introducing the resulting cracked products into said evaporating zone wherein vapors separate from liquid residue, fractionating vapors evolved from said oil in said stripping zone to form a condensate suitable for 70 use as clean cracking stock, passing condensate so derived through a second cracking zone wherein it is raised to a cracking temperature and subjected to conversion while passing in a stream of restricted cross-
- 45 2. A process in accordance with claim 1 wherein the condensate removed from said stripping zone and passed through said second cracking zone includes gas oil fractions and wherein a lighter condensate comprising gasoline constituents is removed from said stripping zone, passed through a third zone in a stream of restricted cross-sectional area wherein it is raised to a relatively high cracking temperature sufficient to cause the reformation thereof and subjected to conversion, and the resulting reformed products are introduced into said evaporating zone.
- 60 3. The process of treating hydrocarbon oil which comprises introducing relatively heavy oil comprising residual constituents and lighter constituents into a stripping zone wherein said oil is separated into vapors and a liquid residue, removing said residue from said stripping zone and passing residue so removed through a first cracking zone wherein it is raised to a cracking temperature and subjected to conversion while passing in a stream of restricted cross-sectional area through a heating zone, introducing the resulting cracked products into an evaporating zone wherein vapors separate from liquid residue, fractionating vapors evolved from said oil in said stripping zone to form a condensate suitable for use as clean cracking stock, passing condensate so derived through a second cracking zone wherein it is raised to a cracking temperature and subjected to conversion while passing in a stream of restricted cross-

sectional area through a heating zone, introducing the resulting cracked products into said evaporating zone to be in admixture therein with the products from said first-mentioned cracking zone, removing liquid residue from said evaporating zone, reducing the pressure on the residue so removed to cause partial vaporization thereof, passing resulting vapors upwardly through said stripping zone to aid in heating and distilling the said heavy oil introduced thereto while preventing mixture with the stock passing through said first and second cracking zones of undistilled portions of said residue last-mentioned, fractionating vapors separated in said evaporating zone to form a final desired 10 light distillate and a reflux condensate, combining said reflux condensate with the oil passing through said second cracking zone, withdrawing from said stripping zone a second and lighter condensate comprising gasoline constituents, 15 passing condensate so withdrawn through a third zone wherein it is raised to a relatively high cracking temperature sufficient to cause the formation of relatively high anti-knock gasoline constituents, and introducing the resulting reformed products into said evaporating zone.

4. The process of treating hydrocarbon oil which comprises passing fresh relatively heavy charging stock into a stripping zone wherein partial vaporization thereof occurs, removing the residual portion of said charging stock and introducing it into an upper level in an evaporating zone wherein hot vapors pass upwardly counter-current to the residual portion so introduced, causing partial vaporization thereof, removing from an intermediate level in said evaporating zone below said upper level unvaporized portions of said residual portion in mixture with condensed fractions of the rising vapors, passing the resulting mixture through a cracking zone wherein it is raised to a cracking temperature and subjected to conversion while traveling in a stream of restricted cross-sectional area through a heating zone, introducing the resulting cracked products into a still lower 40 level in said evaporating zone wherein vapors separate from liquid residue, said vapors passing upwardly through said evaporating zone and constituting a source of said hot vapors first-mentioned, preventing the passage upwardly 45 through said evaporating zone to a point above said intermediate level, of heavy entrained constituents by washing the vapors below said intermediate level with a downwardly flowing stream of refluxing liquid, removing said liquid 50 residue from said evaporating zone and directing it into a flashing zone wherein further separation of vapors from residue takes place and passing vapors thus separated into said stripping zone.

5. The process of treating hydrocarbon oil which comprises introducing fresh relatively heavy charging stock into a stripping zone wherein partial vaporization thereof occurs, removing the residual portion of said charging stock and introducing it into a first fractionating zone wherein hot vapors pass upwardly counter-current to the residual portion so introduced, causing partial vaporization thereof, removing from a lower portion of said first fractionating zone unvaporized portions of said residual portion in mixture with condensed fractions of said hot vapors, passing the resulting mixture through a first cracking zone wherein it is raised to a cracking temperature and subjected 75

- to conversion while traveling in a stream of restricted cross-sectional area through a heating zone, introducing resulting cracked products into an evaporating zone wherein vapors separate 5 from liquid residue, passing resulting vapors into said first fractionating zone as a source of said hot vapors first-mentioned, passing uncondensed vapors from said first fractionating zone into a second fractionating zone wherein separation 10 thereof into fractionated vapors of the desired boiling characteristics and a reflux condensate occurs, condensing said fractionated vapors to form a desired product, removing said reflux condensate and passing it through a second 15 cracking zone wherein it is raised to a cracking temperature and subjected to conversion while traveling in a stream of restricted cross-sectional area through a heating zone, introducing resulting cracked products into said evaporating 20 zone, removing liquid residue from said evaporating zone and introducing it into a flashing zone under reduced pressure wherein partial vaporization of said residue occurs, and passing vapors so obtained through said stripping zone 25 in contact with said fresh relatively heavy charging stock while preventing the passage of any unvaporized portions of said residue last-mentioned through either of said cracking zones.
6. The process of treating hydrocarbon oil 30 which comprises separating from crude oil, without cracking, light gas oil and topped crude, introducing said topped crude into an intermediate point in an evaporating zone over contact surfaces therein to be heated by counter-current 35 contact with hot vapors therein, whereby the said topped crude is subjected to partial vaporization while passing in down-flowing streams against the upwardly-rising vapors, removing heated topped crude from an intermediate point in said zone 40 lower than that first mentioned, cracking the removed topped crude by application of heat, introducing the hot cracked products into a low point in said zone to permit vaporization thereof, contacting with the resulting vapors at a point below 45 and at a point above said intermediate points with a counter-current flow of relatively cool light gas oil derived from said crude oil to cause refluxing thereof, and removing gasoline containing vapors from the top of said zone.
- 50 7. The process of treating hydrocarbon oil which comprises passing gas oil and naphtha comprising essentially heavy fractions of gasoline in separate streams of restricted cross-sectional area through convection and radiant sections of a 55 common heating zone and heating different portions of each of said streams preponderantly by convection heat and radiant heat respectively, to raise them to conversion temperatures and cause cracking of said gas oil and reformation of said 60 naphtha, introducing the reformed naphtha directly into a vapor separating zone, additionally reacting the cracked gas oil in an enlarged unheated soaking zone, introducing the resulting soaked products into said separating zone and 65 removing the separated vapors and fractionating them to form a desired light distillate.
8. The process of treating hydrocarbon oil 70 which comprises contacting crude oil with vapors from a residue flashing operation to cause vaporization of the lighter constituents thereof, condensing from the resulting vapors a heavy naphtha condensate comprising essentially heavy fractions of gasoline, removing unvaporized portions of the crude oil and subjecting them to further 75 vaporization by passing them downwardly
- through a first fractionating zone, over contact surfaces therein, in countercurrent contact with rising highly heated vapors, whereby the liberated vapors quickly separate from a mixture of liquid residue and heavy condensate, removing the said mixture and raising it to a cracking temperature while passing through a heating zone in a stream of restricted cross-sectional area, introducing resulting cracked products into a vapor separating zone, passing vapors from said separating zone 10 into said first fractionating zone as said highly heated vapors, removing liquid residue and flashing it under reduced pressure to form said vapors first mentioned, raising said heavy naphtha condensate to cracking temperatures under reforming conditions in an individual heating zone, introducing the resulting reformed products into 15 said separating zone, and removing fractionated vapors from said first fractionating zone and subjecting them to further fractionation to form 20 a desired light distillate.
9. A process for treating raw crude oil which comprises heating said oil, subjecting the heated oil to distillation to separate therefrom products including heavy naphtha comprising essentially 25 heavy fractions of gasoline, subsequently heating the unvaporized portions of the reduced crude oil to a temperature sufficient to promote mild cracking, passing the heated oil into an evaporating zone, removing vapors from said evaporating zone, 30 and passing them to a fractionating zone to produce a light overhead fraction and a condensate, cracking said condensate in the vapor phase, introducing the resulting heated vapors into said evaporating zone, heating said heavy naphtha to 35 a reforming temperature and introducing the heated naphtha into said evaporating zone, removing liquid residue from the bottom of said evaporating zone, subjecting it, while still hot, to a flashing operation to produce vapors and passing 40 said vapors into contact with said crude oil prior to the heating thereof to the cracking temperature.
10. The process of treating hydrocarbon oil which comprises introducing fresh relatively 45 heavy charging stock into a stripping zone wherein partial vaporization thereof occurs, removing the residual portion of said charging stock and introducing it into an upper level in an evaporating zone wherein hot vapors pass upwardly counter-current to the residual portion so introduced, causing partial vaporization thereof, removing from an intermediate level in said evaporating zone below said upper level unvaporized portions of said residual portion in mixture with condensed fractions of the rising vapors, passing the resulting mixture through a cracking zone wherein it is raised to a cracking temperature and subjected to conversion while traveling in a stream of restricted cross-sectional area through a heating zone, introducing the resulting cracked products into a still lower level in said evaporating zone, wherein vapors separate from liquid residue, fractionating vapors liberated in said evaporating zone to form a final desired light distillate and 60 a reflux condensate, withdrawing liquid residue from said evaporating zone, reducing the pressure on the residue so withdrawn to cause partial vaporization thereof, passing resulting vapors upwardly through said stripping zone to aid in the 65 distillation of said fresh relatively heavy charging stock, and blending with the unvaporized portions of said residue last-mentioned at least a portion of said reflux condensate to form fuel oil and isolating the fuel oil from the process, 75

5 withdrawing clean reflux condensate from said stripping zone and passing it through a third zone wherein it is raised to a cracking temperature and subjected to conversion, and introducing resulting hot products of conversion into said evaporating zone at a point below said intermediate level.

10 11. The process of treating hydrocarbon oil which comprises passing a condensate stock through a cracking zone wherein it is raised to a cracking temperature and subjected to conversion, introducing resulting cracked products into an evaporating zone wherein separation of vapors from liquid residue occurs, passing separated vapors from said evaporating zone into a fractionating zone wherein the vapors are subjected to fractionation to form a reflux condensate and fractionated vapors, condensing said fractionated vapors to form a desired distillate, directing said 15 20 reflux condensate to said cracking zone, removing liquid residue from said evaporating zone and in-

5 troducing it into a flash zone under reduced pressure wherein partial vaporization of said residue occurs, passing resultant vapors into a stripping zone, introducing charging stock containing gasoline constituents into said stripping zone in contact with the vapors therein to effect partial vaporization thereof, removing the resultant residue portion of said charging stock and introducing it into said evaporating zone to dephlegamate separated vapors therein and effect further vaporization thereof, fractionating vapors evolved in said stripping zone to form a distillate containing gasoline constituents, passing said distillate through a reforming zone wherein it is raised to a cracking temperature sufficient to cause the reformation thereof and is converted into products of increased anti-knock quality and directing the resultant products of the reforming into said evaporating zone.
